UNITED STATES PATENT OFFICE.

WILLIAM K. PINE, OF LOCKPORT, NEW YORK, ASSIGNOR TO OLIVER BROTHERS, OF SAME PLACE.

DESIGN FOR A BICYCLE-STAND.

SPECIFICATION forming part of Design No. 27,770, dated October 19, 1897.

Application filed July 19, 1897. Serial No. 645,179. Term of patent 7 years.

To all whom it may concern:

Be it known that I, WILLIAM K. PINE, a citizen of the United States, residing at Lockport, in the county of Niagara and State of New York, have invented and produced a new and original Design for Bicycle-Stands, of which the following is a specification, reference being had to the accompanying drawing, forming a part thereof.

10 This design relates to the configuration of a bicycle-stand, the accompanying drawing being a perspective view of a bicycle-stand embodying my design.

15 The distinctive feature of my design consists in the peculiar shape of the upright or holding portion of the stand.

20 Referring to the drawing, A represents the base-frame, consisting of four bars *a*, four supporting-feet *b* at the corners thereof, and two pedestals *c*, arranged centrally on two opposite bars *a*.

The upright or supporting portion of the stand consists of a number of upright bars *E*, which are arranged in pairs, an upwardly-curved portion *e*, connecting the upper ends 25 of each pair of bars, and downwardly-curved portions *e'*, connecting the lower ends of the adjacent bars of the several pairs, forming a series of supporting loops or racks.

The lower connecting-loops *e'* may extend 30 to the intermediate cross-bar *d*, and the outer bars of the outermost loops are mounted with their lower ends on the pedestals.

I claim as my invention—

The design for a bicycle-stand, substantially as herein shown and described.

Witness my hand this 13th day of July, 1897.

WILLIAM K. PINE.
